UNITED STATES PATENT OFFICE.

ARTHUR LANG, OF NEW YORK, N. Y.

TUNING MECHANISM FOR STRINGED INSTRUMENTS.

SPECIFICATION forming part of Letters Patent No. 726,706, dated April 28, 1903.

Application filed December 1, 1902. Serial No. 133,334. (No model.)

To all whom it may concern:

Be it known that I, ARTHUR LANG, a citizen of the United States, and a resident of New York, Brooklyn borough, in the county of Kings and State of New York, have invented certain new and useful Improvements in Tuning Mechanism for Stringed Instruments, which improvements are fully set forth in the following specification.

10 This invention relates to improvements in stringed musical instruments, and particularly to the mechanism employed for adjusting the tension of the strings of such instruments.

15 The object of this invention is to provide mechanism of the character indicated which shall be simple and inexpensive as regards construction, which shall be durable, efficient, and reliable in practical service, which 20 shall embody features of construction whereby marked permanency in the conjecture of the operative parts thereof shall be insured, which shall be attractive in appearance, and which shall possess certain well-defined advantages over prior analogous mechanisms.

25 The invention consists in the novel disposition and arrangement of the various operative parts thereof, whereby the attainment 30 of the foregoing objects is rendered practicable, in certain combinations, and in certain details of construction, all of which will be specifically referred to hereinafter and set forth in the appended claims.

35 The invention is clearly illustrated in the accompanying drawings, wherein similar reference-numerals denote corresponding parts throughout the several views, and as to said drawings—

40 Figure 1 is a perspective view of a tuning mechanism embodying my said improvements. Fig. 2 is a face view of the gear-wheel which forms an element of my improved mechanism. Fig. 3 is a detail view, 45 partly in section, showing certain of the parts in readiness for permanent conjunction. Fig. 4 is a view in perspective, illustrating the form and construction of the string-post, which constitutes an element of my improved 50 mechanism.

Having reference to the accompanying drawings, 2 denotes a base-plate of any ap-

propriate construction and ordinarily formed from sheet metal. It is designed to be affixed to the neck-piece of a banjo, guitar, or other 55 stringed musical instrument in the usual manner. There is arranged to bear rotatively in the base-plate 2 a string-post, which comprises a main portion 3 of a given diameter, a many-sided portion 3' of a less diameter than the 60 main portion 3, and an extension 3" of a less diameter than and projecting beyond the many-sided portion 3'.

In practice the many-sided portion of the string-post aforesaid projects outwardly 65 through the plate 2 by way of a suitable opening formed in the latter, and the circumferential segments of said many-sided portion bear rotatively on said plate at the opening just mentioned as being formed therein. 70

There is mounted on the many-sided portion of the string-post at the outer side of the plate 2 a gear-wheel 4, which has an irregular central opening, such opening by preference conforming in general contour to the cross-sectional contour of the many-sided portion 75 of the string-post, and said gear-wheel has a recessed outer face, as indicated in Figs. 2 and 3 of the drawings.

It will here be observed that the length of the 80 many-sided portion of the string-post is somewhat less than the thickness of the gear-wheel 4 from the base of the latter's recess to the rear side thereof, which variation in dimensions insures the seating of the washer 4' on 85 the base of the recess of the gear-wheel 4, said washer being let onto the extension 3" at the outer side of the gear-wheel 4.

The foregoing construction is important, for the reason that where it is availed of the 90 washer 4' serves to obviate undue setting or locking of the parts against rotative action under the operation of upsetting the outer end of the extension 3", which is resorted to in assembling the parts permanently for 95 practical service, said washer accordingly seating directly and only on the gear-wheel 4 and being formed from material somewhat resilient or yielding, as thin sheet metal. Further, the yielding action of the washer 4' 100 on the gear-wheel 4 under the secured condition of the latter with respect to the string-post prevents any voluntary shifting movement of said post with respect to the plate 2,

any like movement of the gear-wheel 4 along the many-sided portion of the string-post, and at the same time permits the string-post, with the gear-wheel 4 mounted thereon, to be freely rotated in either direction.

5 The washer 4' constitutes a separate element of my improved mechanism and may be colored in contrast with the gear-wheel 4, thus enhancing the appearance of the mechanism as a whole, and by employing the washer 4' and other details of construction herein specified I obtain an elastic adjustment of the gear-wheel 4 with respect to the string-post which I make use of.

10 15 As an element whereby the string-post may be rotated in opposite directions in the practical operation of the mechanism and through the medium of the gear-wheel 4 I employ the usual worm-threaded stem 4'', bearing rotatively in opposing lugs 5 5', with which the plate 2 is provided, the threads of said stem being at all times in mesh with the gear-wheel 4. Said stem is also provided with the usual finger-piece 6.

20 25 It will be seen that my improved mechanism is particularly well adapted for the purposes for which it is designed and, further, that the same may be modified to some extent without materially departing from the spirit and principle of my invention.

Having fully described my invention, what I claim, and desire to secure by Letters Patent, is—

30 35 1. A tuning mechanism for stringed musical instruments comprising a base-plate; a string-post projecting outwardly through said plate and bearing rotatively therein; a gear-wheel elastically adjusted on said string-post,

at the outer side of said base-plate; and means for rotating said string-post through the medium of said gear-wheel, substantially as herein specified.

2. A tuning mechanism for stringed musical instruments comprising a base-plate; a string-post having a many-sided portion, projecting outwardly through said base-plate, and bearing rotatively therein; a gear-wheel on said many-sided portion of the string-post, at the outer side of said base-plate; a yielding washer at the outer side of said gear-wheel, on said post and bearing upwardly against said gear-wheel, the latter being thicker than the length of said many-sided portion of the string-post; means for holding said washer in place; and means for rotating said string-post through the medium of said gear-wheel, substantially as herein specified.

3. A tuning mechanism for stringed musical instruments comprising a base-plate; a string-post having a many-sided portion projecting outwardly through said base-plate and bearing rotatively therein; a gear-wheel on said many-sided portion of the string-post, at the outer side of said plate, said post having a reduced extension projecting beyond its many-sided portion; a yielding washer on said post extension and bearing inwardly against said gear-wheel, said extension being upset at its outer end for holding said washer in place; and means for rotating said string-post through the medium of said gear-wheel, substantially as herein specified.
